HEATING STRUCTURE

Daniel W. Myers, Hicksville, Ohio

Application July 14, 1936, Serial No. 90,576

5 Claims. (Cl. 126—109)

This invention relates to the class of heating structures and pertains particularly to an air heater although the structure may be employed with slight modification for heating liquids.

5. The primary object of the present invention is to provide an air heating structure wherein a novel means is employed for circulating the air to be heated and for circulating the gases produced as a result of the combustion of fuel, where-
10 by the maximum of the heating units will be ex-
tracted from the gases by the air, before the gases are discharged to the atmosphere.

Another object of the invention is to provide in an air heating furnace or stove structure a novel annular casing into which the products of combustion pass in flowing to the chimney outlet of the structure, which casing is so designed that the air to be heated will impinge upon one wall in a manner to direct it therefrom against another heated wall whereby a baffled passageway is formed for the air which will result in the fluid taking up more heat than would be the case if its path through the furnace structure were unob-
20 structed.

25. A still further object of the invention is to provide in a furnace or stove structure, a novel means of concentrating the heat produced from the combustion of fuel, around tubular passageways through which the air is passed to be heated.

30. The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the ap-
35 pended claims.

In the drawings:—
Figure 1 is a vertical sectional view through the structure embodying the present invention;
Figure 2 is a top plan view of the structure
45 with the head removed;

Figure 3 is a sectional view taken on the line
3—3 of Figure 1;

Figure 4 is a detailed sectional view through the upper end of a pipe and top wall of the drum showing the coupling means employed between these units.

Referring now more particularly to the drawings, the numeral 1 designates the outer housing or casing for the furnace, which casing may be of sheet metal or cast in the cylindrical form in
55

which it is shown. The bottom of the casing 1 is open and rests upon any suitable flat supporting surface such as a cement floor or base, not shown.

The top of the casing 1 is closed by the head 2 which is in the form of a dome and which is provided with one or more heated air outlets 3. At a suitable point below the top edge the casing is provided with a flue pipe 4 through which the products of combustion are carried off, and adjacent the bottom the casing has an inlet 5 for air and an opening 6 through which a fuel conducting pipe may pass.

Within the casing 1 in a plane above the openings 5 and 6, is a horizontal partition 7 which has a central opening 8 formed therethrough and disposed vertically in and passing through the opening 8 is a cylinder 9 which forms a combustion chamber and which rests at its lower end upon the same surface as the casing 1. In this chamber may be placed any suitable type of fuel burner, such as a gas or oil burner, which is illustrated conventionally in broken lines and indicated by the numeral 10.

Disposed centrally in the casing 1 above the partition 7 is a drum which is indicated generally by the numeral 11 and which is of slightly smaller diameter at its top than at its bottom so that the wall thereof tapers inwardly from the bottom edge to the top and the top is closed by the head or sheet 12. Closing the lower part of the drum 11 is a bottom wall or sheet 13 which is disposed in a plane slightly above the plane of the bottom edge of the drum, and this wall 13 is centrally apertured to receive the upper end of the combustion chamber forming cylinder 9 in the manner illustrated. The joint between the top edge of the cylinder 9 and the opening in the wall 13 is made tight so that no air can enter the drum from inside the housing or casing 1.

Extending from the bottom wall 13 of the drum to the top wall or sheet 12 is a series of tubes or pipes 14 which are disposed in upwardly convergent relation and which open at their upper and lower ends respectively through the walls 12 and 13. These tubes are of smaller diameter at their lower ends than at their top ends, the diameter gradually increasing at a constant rate from one end to the other, and this construction serves to effect smoother flow of air through the structure as it allows the air to expand as it becomes heated without choking the pipes.

Means is illustrated for mounting the pipes 14 and for effecting a tight joint between their
55

ends and the walls to which the ends are joined. As illustrated, the bottom wall 13 is provided with an annular channel 15 which encircles each of the openings through which the lower end of a tube 14 opens and the top overlying the opening has its bottom edge resting in this annular channel and a tight joint is made by filling the channel around the inside and outside surfaces of the tube with a suitable sealing material 10 which may be in the form of sand, ashes or a cement.

At their top ends the tubes 14 are each provided with an outwardly and downwardly turned collar 16 and the top surface of the sheet 12 has an annular channel 17 around the opening through which the upper end of the tube passes and this channel, being upwardly directed, has the free bottom edge of the collar 16 of the adjacent tube disposed therein and is filled at 20 the inner and outer sides of the collar by a sealing material 18 such as has been previously referred to.

Encircling the drum 11 is a cylindrical shield 19 which is open at its top and bottom and which is of an exterior diameter at its bottom equal to the interior diameter of the casing 1 with which it is in contact. This shield tapers upwardly at the same or substantially the same inclination as the side wall of the drum 11 so that the wall of 30 the drum and the shield are substantially parallel, and the top end of the shield projects a substantial distance above the top plane of the drum while the lower edge of the shield is in a plane which passes through the lower central 35 portion of the drum in the manner illustrated.

Formed integral with the shield 19 is an annular heat casing, which is indicated generally by the numeral 20, and which has the upwardly and inwardly inclined inner wall 21 which 40 merges at its lower edge with the wall of the shield and which joins at its top edge with a horizontal wall 22 which connects with the shield 19 so as to form with the shield and the inclined wall 21 the heat casing of substantially 45 triangular cross section. As illustrated, the wall 21 of the heat casing is sharply inclined so that the hot air flowing upwardly through the area between the drum 11 and the casing 1 will strike this sharply inclined heat casing wall and be 50 deflected inwardly against the wall of the drum.

Extending upwardly and inwardly from the top wall 22 of the annular casing 20 are flue tubes 23 which open into the casing 20 at their lower ends and which are sharply angled at 55 their upper ends to open through apertures in the heat drum 11 adjacent the top thereof. These tubes 23 constitute down draft tubes or passageways through which the hot gases will pass from the drum 11 into the casing 20 and 60 after entering this casing they will flow therefrom through the vertically extending chimney pipe 24 which opens at its lower end through the top wall 22 of the heat casing and then pass laterally through the cylindrical shield at the 65 proper elevation to enter the flue connection 4.

From the foregoing description it will be readily apparent that air entering the lower part of the heater will follow two paths before it passes out through the openings 3 at the top of 70 the casing. Part of the air will be caught in the lower part of the drum 11 beneath the wall 13 and will flow upwardly through the tubes 14 and part will flow upwardly on the outside of the drum, striking the wall 21 of the annular heat 75 casing as previously described to the deflected

inwardly toward the wall of the drum and then passing upwardly from this wall around the pipes 23 through which the hot gaseous products of combustion are flowing downwardly to the interior of the casing 20. By arranging the 5 cylindrical shield 19 in the manner illustrated, the air will be crowded inwardly around the tubes 23 and the upper part of the drum 11 so that the maximum of heating units will be extracted from the heated tubes and drum before 10 the air reaches the top of the casing to pass out through the openings 3 and into the distributing pipes, not shown, which are normally provided for conducting the air to points of distribution.

While the drawings illustrate a heater of circular construction and having the shield, heating drum and tubes all circular, it is to be understood that the invention is not to be limited to a heater of this specific formation as it is obvious that the tubes and drum and other parts may 20 be made of rectangular cross section if found desirable or necessary.

I claim:—

1. A heating structure of the character described comprising a vertical casing having a 25 closed top and provided with air outlets, means forming a fuel combustion chamber in the lower part of the casing, a drum within the casing having top, bottom and side walls, said bottom wall being connected with the combustion chamber 30 and having an opening leading into the chamber, a plurality of tubes connecting and opening through the top and bottom walls of the drum and passing through the latter, a casing within the first mentioned casing, a pipe coupling the 35 second mentioned casing with the products of combustion outlet passing through the first mentioned casing wall, said second mentioned casing being disposed in a plane between the top and bottom walls of the drum, and a plurality of 40 pipes opening into and extending downwardly from the top part of said drum and opening into the second mentioned casing, said pipes forming down draft passages from the interior of the drum to said second mentioned casing, said second mentioned casing being in spaced encircling 45 relation with the drum and having an inner upwardly and inwardly inclined wall arranged to deflect upwardly flowing air against the adjacent drum wall.

2. A heating structure of the character described comprising a casing having a closed top provided with outlet openings, a vertically disposed cylinder in the lower part of the casing forming a fuel combustion chamber, a drum disposed above the cylinder and having top, bottom and side walls, said bottom wall being connected with the top of the cylinder and having the latter opening therethrough, said drum side wall being upwardly and inwardly inclined, a plurality of tubes extending through the drum and connecting and opening through the top and bottom walls thereof, a casing within the first casing and surrounding said drum, said second casing being in spaced relation with the drum and disposed in contact throughout its circumference with the inner side of the first casing, means opening from the second mentioned casing for carrying off products of combustion therefrom, said second mentioned casing being disposed in a plane 70 passing transversely through and substantially midway between the top and bottom of the drum, a plurality of pipes opening through the side wall of the drum adjacent the top thereof and extending downwardly to and opening into the 75

second mentioned casing, said second mentioned casing having an inner wall arranged in upwardly and inwardly inclined position relative to the drum and in close proximity thereto to deflect upwardly flowing air against the adjacent wall of the drum.

3. A heating structure of the character described comprising a casing having a closed top provided with outlet openings, a vertically disposed cylinder in the lower part of the casing forming a fuel combustion chamber, a drum disposed above the cylinder and having top, bottom and side walls, said bottom wall being connected with the top of the cylinder and having the latter opening therethrough, said drum side wall being upwardly and inwardly inclined, a plurality of tubes extending through the drum and connecting and opening through the top and bottom walls thereof, a casing within the first casing and surrounding said drum, said second casing being in spaced relation with the drum and disposed adjacent the inner side of the first casing, means opening from the second mentioned casing for carrying off products of combustion therefrom, said second mentioned casing being disposed substantially midway between the top and bottom of the drum, a plurality of pipes opening through the side wall of the drum adjacent the top thereof and extending downwardly to and opening into the second mentioned casing, said second mentioned casing having an inner wall arranged in upwardly and inwardly inclined position and adapted to deflect upwardly flowing air against the wall of the drum, and 35 a shield encircling the upper portion of said drum and extending from the outer side of the second mentioned casing and further being of less diameter at its top than at its bottom whereby to converge upwardly flowing air passing therethrough inwardly toward the drum.

4. A furnace structure comprising a casing having a centrally apertured wall therein and disposed above the bottom thereof, said casing having an air inlet beneath said wall, a vertical hollow upwardly opening structure extending from the bottom of the casing upwardly through said apertured bottom wall and spaced from the edge of the aperture, outlet openings in the up-

per part of the casing, a vertically disposed drum having top, bottom and side walls and having its bottom wall connected with the top of said hollow structure, the latter structure opening into the drum and constituting a combustion chamber, tubes extending vertically through the drum and opening through the top and bottom walls thereof, means forming an annular chamber around and in spaced relation with the drum in a plane between the top and bottom walls thereof, the outer side of the annular chamber being in contact with the casing, said annular chamber having an under wall inclined from the casing toward the drum, a passageway connecting the interior of the annular chamber with the outside atmosphere through the casing, and tubes coupling the upper part of said drum with said annular chamber and extending downwardly and outwardly from the drum.

5. A heating structure of the character described, comprising a vertical casing having a closed top and provided with air outlets, means forming a fuel combustion chamber in the lower part of the casing, a drum within the casing having top, bottom and side walls, said bottom wall being connected with the combustion chamber and having an opening leading into the chamber, a plurality of tubes connecting and opening through the top and bottom walls of the drum and passing through the drum, a casing within the first mentioned casing in spaced surrounding relation with the drum and lying in a plane between the top and bottom walls of the drum, a pipe coupling the second mentioned casing with a products of combustion outlet passing through the first mentioned casing wall, said second mentioned casing being so constructed and arranged as to deflect upwardly moving air in the first casing against the side of the drum as the air passes between the air casing and drum, and a plurality of pipes opening into and extending upwardly from the top part of the drum and opening into the second mentioned casing, said pipes forming down-draft passages from the interior of the drum to said second mentioned casing.

DANIEL W. MYERS.
